UNITED STATES PATENT OFFICE.

HERMAN H. LARKINS, OF PRINCETON, KENTUCKY.

MUFFLER.

1,021,254.

Specification of Letters Patent. Patented Mar. 26, 1912.

Application filed September 2, 1911. Serial No. 647,311.

To all whom it may concern:

Be it known that I, HERMAN H. LARKINS, a citizen of the United States, residing at Princeton, in the county of Caldwell and 5 State of Kentucky, have invented certain new and useful Improvements in Mufflers, of which the following is a specification, reference being had to the accompanying drawings.

10 This invention relates to new and useful improvements in mufflers and has for its object to provide a new and improved muffler so arranged as to effectively muffle or deaden the exhaust of explosive engines, or other 15 engines and machines without causing any back pressure in the engine cylinder.

Another object of the invention is to provide a device of this character which will possess advantages in points of efficiency, 20 durability, is inexpensive of manufacture and at the same time is simple in construction and operation.

With the above and other objects in view the invention consists in the novel features 25 of construction and the combination and arrangement of parts hereinafter described and pointed out in the claims and shown in the accompanying drawings in which—

Figure 1 is a side elevation of my improved muffler; Fig. 2 is a longitudinal sectional view; Fig. 3 is a sectional view on the line 3—3 of Fig. 2, Fig. 4 is a longitudinal sectional view of a modified form.

Referring more particularly to the drawings 35 1 indicates an exhaust pipe to carry the products of combustion from the combustion chamber of the cylinder of an internal-combustion engine. The extremity of the exhaust pipe is led into a muffler drum or 40 chamber 2. The exhaust pipe 1 is disposed in the drum over half way so as to bring the exhaust well into the chamber 2 where it circulates and then passes out through the conductor 3 into the second or additional 45 muffler drum 4. This conductor 3 is disposed into the second drum over half way so as to bring the exhaust well into the drum 4 where it circulates back to the other end of the drum and passes out through the discharge pipe 5, communicating with the atmosphere at its outer end. Jam nuts 6 are 50 arranged upon the conductor 3 and disposed between the drums to keep them in position at an equal distance apart and also to keep 55 the conductor up in position. Jam nuts 7 are arranged on the outer end of the pipes

1 and 5 and screwed tightly up against the outside of the drums to hold the pipes in place.

I have herewith shown and described two chambers, the one communicating into the other through the conductor 3, and I have shown means whereby the second drum 4 discharge to the atmosphere. I do not, however, limit myself to the employment of two muffler chambers, inasmuch as for some purpose a single chamber with its connected parts may be found to be sufficient, and in other cases it will readily be seen that the discharge pipe 5 might lead into an additional muffler drum constructed and arranged with parts corresponding to the drum 4. My invention therefore contemplates as coming within its scope the employment of either a single muffler drum 75 with its connecting parts or any desired multiple of drums connected up in a similar manner to that illustrated in the accompanying drawings.

It will be perceived when the products of 80 combustion are discharged into the drum 2 from the exhaust pipe 1 there is no appreciable back pressure. The gases discharged into the muffler drum it will be readily seen pass through the drum in a 85 roundabout way, by first being discharged through the drum to one end and then circulating back to the other end where it enters the conductor 3 and passes out into the drum 4, where it is circulated as in the 90 first drum and then passes off to the atmosphere.

In Fig. 4 is shown a slightly modified form of muffler wherein 8 indicates an exhaust pipe which communicates with the 95 muffler drum 9 at one side and near one end thereof. The exhaust passes in the drum at one end and circulates to the other end where it enters a conductor 10 which carries it to the farther end of a second muffler 100 drum 11 and from there circulates back to the other end of the drum and is discharged through the pipe 12 located in the side of the drum near one end thereof. This form of muffler is to be used in place of the first 105 form when it is so desired.

While I have shown and described the preferred form of my invention it will be obvious that various changes in the details of construction and in the proportions may 110 be resorted to for successfully carrying the invention into practice without sacrificing

any of the novel features or departing from the principles thereof.

Having thus described my invention, I claim:—

- 5 1. A muffler comprising spaced drums arranged in longitudinal alinement, a conducting pipe extending through the opposed ends of the drums and into the same beyond their longitudinal centers, nuts threaded upon the intermediate portion of said pipe and engaging the drum heads to maintain the drums in spaced relation, an exhaust pipe connected to one of the drums, and a discharge pipe connected to the other drum.
- 10 2. A muffler comprising a plurality of drums arranged in longitudinal alinement and in spaced relation, a conducting pipe connecting adjacent drums and extending through the opposed end walls thereof and into the respective drums beyond their longitudinal centers, nuts threaded upon the intermediate portion of the conducting pipe and engaging the drum heads to maintain the drums in spaced relation, an exhaust
- 15 20 25 pipe extending through the opposite end wall of one of the drums and in parallel relation to the conducting pipe, and a discharge pipe extending into the other drum in longitudinal alinement with said exhaust

pipe, said exhaust and discharge pipes extending beyond the ends of the conducting pipe and terminating at points adjacent the connected ends of the respective drums.

3. A muffler comprising a plurality of drums arranged in longitudinal alinement, a conducting pipe eccentrically disposed through the opposed end walls of adjacent drums, said pipe extending into the respective drums beyond their longitudinal centers, nuts threaded upon the intermediate portion of said pipe to engage the opposed end walls of the drums to maintain the drums in spaced relation, an exhaust pipe concentrically disposed through the other end wall of one of the drums, a discharge pipe concentrically disposed through the corresponding end wall of the other drum, said exhaust and discharge pipes overlapping the conducting pipes and terminating within their respective drums at points adjacent to the connected ends thereof.

In testimony whereof I hereunto affix my signature in the presence of two witnesses.

HERMAN H. LARKINS.
